UNITED STATES PATENT OFFICE.

ARTHUR ERNEST JERRAM, OF LEICESTER, ENGLAND, ASSIGNOR, BY MESNE ASSIGNMENTS, TO UNITED SHOE MACHINERY CORPORATION, OF PATERSON, NEW JERSEY, A CORPORATION OF NEW JERSEY.

NEEDLE FOR LACING SHOE-UPPERS.

1,289,183.

Specification of Letters Patent. Patented Dec. 31, 1918.

Application filed December 2, 1914. Serial No. 875,199.

To all whom it may concern:

Be it known that I, ARTHUR E. JERRAM, a subject of the King of Great Britain, residing at Leicester, in the county of Leicestershire, England, have invented certain new and useful Improvements in Needles for Lacing Shoe-Uppers; and I do hereby declare the following to be a full, clear, and exact description of the invention, such as will enable others skilled in the art to which it appertains to make and use the same.

This invention relates to appliances for lacing boot and shoe uppers, and particularly to that type of lacing appliance which comprises a plurality of barbed needles for carrying through the work a number of loops of lacing material which are secured in place by threading through them a length of lacing material or other fastening device.

In this type of lacing appliance the needles are arranged parallel to one another with their axes approximately in one plane, and in order that the lacing material may enter the thread grooves in the needles with facility, the needles are so disposed that the plane containing the barb and the shank of each needle is approximately at right angles to the plane containing the axes of the needles. Consequently with needles of usual form, the openings through the needles that form the thread grooves are in alinement so that the two sides of all the loops carried through the work are in the same plane, that is to say, in the plane of the axes of the needles. From this cause, difficulty is experienced in threading the fastening material through the loops so formed unless mechanism is provided for rotating each of the needles.

It is an object of this invention to overcome this difficulty, and according to one feature of the invention, in a lacing appliance of the type specified the needles are so formed and disposed that while the end portion of each needle barb projects as heretofore away from the plane in which the axes of the needles lie, the portion or bend of each needle that connects the barb to the shank is arranged to lie substantially in the general plane of the said axes. In

this way while the tip of each needle barb is in a suitable position to receive the lacing material the part of the opening forming the end of the thread groove into which the lacing material is drawn while it is being carried through the work has such a direction that the loops are formed at a substantial angle to the plane in which the series of loops lies, so that the fastening material may be threaded through the loops without it being necessary, as in prior constructions, to turn each needle about its axis to twist the loop carried by it, or to cause the fastening material itself to take a sinuous course.

A further feature of the invention consists of a needle for use in lacing boot and shoe uppers comprising a barb the end portion of which projects out of the plane containing the shank of the needle and the base portion or bend connecting the barb to the shank.

An example of a lacing appliance embodying the present invention and of the preferred form of lacing needle will now be described with reference to the accompanying drawings, in which:

Figure 1 is a plan of the preferred form of needle;

Fig. 2 is a side elevation of the same;

Fig. 3 is a section through the needle at the base portion connecting the shank to the barb, and

Figs. 4 and 5 are perspective views of a lacing appliance embodying the present invention in the preferred form and illustrating two steps in the lacing of an upper.

Like reference characters indicate like parts in all the figures.

The needle shown in the drawings may readily be constructed by forming a reduced portion A¹ on the end of the shank A. Part of this reduced portion is bent back to form the barb B and twisted axially of the needle so that the base portion C where it is joined to the shank of the needle is approximately at right angles to the plane containing the tip of the barb and the needle shank, as shown in Figs. 1 and 2.

A space D is left between the barb and the shank to form the thread groove. In order

100

that the loops of lacing material may be opened as widely as possible to permit easy passage of the fastening material through the loops, it is advantageous to widen out laterally the portion C of the needle at the bend which forms the junction of the barb and the shank, as shown in Figs. 2 and 3.

In Figs. 4 and 5 is shown a lacing appliance of the type specified which comprises a number, in the example shown three, of lacing needles constructed substantially as above described. The needles may conveniently be mounted in a support or block E, the distance between adjacent needles being equal to the distance apart of adjacent eyelet holes in the boot and shoe uppers to be laced. In the use of the appliance, the corresponding eyelet holes in the two sides of a shoe upper F are brought together and the eyelet holes which it is desired to lace are passed over the needles. A length of lacing material G is next passed over or laid upon the shanks of the needles, as shown in Fig. 4. The upper is then withdrawn from the needles, the lacing material passing down the thread grooves in the needles and being formed into three loops G¹, as shown in Fig. 5, the formation of the needles twisting the said loops through an angle of substantially ninety degrees into suitable position to receive the fastening device. A portion G² of the same or another piece of lacing material is then passed through the loops and the free ends of the lacing material secured together. The loops are now removed from the needle barbs, the two sides of the upper are flattened out, and the lacing of the upper is complete. Although in the appliance shown, a piece of lacing material has been used as the fastening device for the loops, it will be understood that any other suitable fastening device may be employed, as for example a metal pin, the particular device employed being immaterial as far as the present invention is concerned.

Having explained the nature and object of the invention and specifically described

one form in which it may be embodied what is claimed is:

1. A straight needle adapted to pass through the eyelet hole of an upper and draw a loop of lacing thread therethrough having a barb the end portion of which projects out of the plane containing the shank and base portion connecting the barb to the shank.

2. A needle for use in lacing boot and shoe uppers, having a shank, and barb and a transversely enlarged base connecting the shank and barb, the end of the barb projecting out of the plane of the base and shank.

3. An appliance for lacing boot and shoe uppers, comprising a plurality of needles arranged side by side and having barbs the end portions of which project out of the general plane of the series of needles and having the base portions or bends connecting the barbs and shanks arranged substantially in said plane.

4. An appliance for lacing boot and shoe uppers comprising a plurality of needles arranged side by side to pass through the eyelet holes of an upper and having their barbs in position to receive the lacing thread, and having the ends of their thread grooves which draw the loops of lacing thread through the eyelet holes arranged to hold the loops in line with each other and at a substantial angle to the plane of the series to permit the fastening material to be threaded through the loops.

5. An appliance for lacing boot and shoe uppers comprising a series of barb needles arranged parallel to one another with their axes approximately in one plane, and having their barbs arranged to receive a thread extending along the series, and having their bend or base portions connecting the barbs and shanks substantially in the plane of the axes.
